UNITED STATES PATENT OFFICE.

ALBERTO NORIEGA, OF NEW YORK, N. Y.

ORE CLASSIFIER.

Application filed August 16, 1920. Serial No. 403,705.

To all whom it may concern:

Be it known that I, ALBERTO NORIEGA, a citizen of the Republic of Peru, residing at New York, in the county of New York and

5 State of New York, have invented new and useful Improvements in Ore Classifiers, of which the following is a specification.

This invention relates to ore pulp classifiers of the multiple cone type, and one of 10 the objects is to produce a device of this type in which the pulp will be forced upwardly from a nozzle through water against a conical deflector plate from which the various fragments will be cast off to different 15 distances according to their specific gravity.

Another object is to provide a plurality of coaxial cones for receiving the various fragments and conducting them to respective receptacles.

20 Another object is to provide an adjustable conical deflector plate.

Other objects will appear from the following description and claims. All of these 25 objects are attained by the means shown in the accompanying drawing comprising one sheet, in which:—

Figure 1 is a vertical sectional view of my improved classifier.

Figure 2 is a horizontal sectional view of 30 the same taken in line 2—2 of Figure 1, looking down.

Like characters of reference refer to like parts in both views.

Referring to the drawing in detail, 1 represents the framework which may be of any 35 size or shape suitable to support the working parts hereinafter described. A tank 2 is supported on said frame by brackets 3 or in any other desirable manner. This tank is 40 provided at its top with a collar 4 which is secured to the tank by soldering, riveting or in any other desirable manner, a space or channel 5 being defined between members 2 and 4. The bottom of collar 4 is inclined 45 toward one side, and at its lowest point is provided with a spout 6. Mounted on the top of collar 4 is a bridge 7 which crosses the top of the receptacle and is provided in the line of the axis of the tank 2, with an internally threaded bearing 8 in which is 50 mounted a threaded rod 9 provided at its lower end with a deflector plate 10 in the form of an inverted cone and at its upper end with an adjusting hand wheel 11 or 55 other manipulative device.

The bottom of the tank 2 is an inverted

cone 12 the lower portion of which is projected into a cylinder 13, the bottom 14 of which is sloping and provided with a spout 15 which is fitted with a valve 16.

60 Mounted in the member 12 is a similar member 17 having a spout 18 and valve 19, said member 17 being held in place by webs 20 which are secured to members 12 and 17 as shown in the drawing. Similarly, a third 65 member 21 is supported in member 17 and is provided with a spout 22 and valve 23.

A reservoir 24' is adapted to contain the ore pulp and water and this material is forced under pressure through a pipe 24 70 into a riser 25 provided with a nozzle 26 by which the material is directed against the deflector plate 10.

In use the tank 2 is filled with water and then the ore pulp and water is started 75 through piping 24 and riser 25. The mud and small particles are washed by the force of the current over the upper edge of member 2 into passage 5 and out through spout 6.

The heaviest lumps, when they strike 80 plate 10 will be arrested and owing to their weight will overcome the force of the current and settle in cone 21, while the lighter fragments will be carried over the cones 17 and 12 by the current.

85 By opening the valves 23, 19 or 16, the contents of the respective cones may be drawn off. By raising or lowering plate 10 by the handle 11, the graduation of the particles received by each cone may be changed, 90 or this may be accomplished by increasing or decreasing the pressure on the pulp.

It is, of course, to be understood that the device may be made in any size desired and with any desired number of cones for separating the ore as required.

95 While I have described what I deem to be the most desirable embodiment of my invention, it is obvious that many of the details may be varied without in any way departing from the spirit of my invention, and I therefore do not limit myself to the exact details of construction herein set forth, nor to anything less than the whole of my invention limited only by the appended 100 claims.

105 What is claimed as new is:—

110 1. In an ore classifier, the combination of a tank having a circular wall and a conical shaped bottom, a trough encircling said tank at the top thereof, a plurality of conical receptacles mounted in said conical bottom

- and spaced in converging relation to said bottom and to each other, said receptacles being normally closed at their bottoms, a conical deflector plate adjustably mounted above said conical receptacles, and means for forcing particles of ore pulp against said deflector plate whereby the same will be arrested within said receptacles according to their specific gravity.
- 10 2. In an ore classifier, the combination of a tank having a circular wall and a conical shaped bottom, a trough encircling said tank at the top thereof, a plurality of conical receptacles mounted in said conical bottom and spaced in converging relation to said bottom and to each other, said receptacles

being normally closed at their bottoms, a conical deflector plate adjustably mounted above said conical receptacles, and means for forcing particles of ore pulp against said deflector plate, said means comprising a reservoir for the reception of the ore pulp and water, and a pipe connected with said reservoir and leading into said tank and terminating in vertical alignment with the axis 25 of said conical deflector plate, whereby the ore pulp will strike said conical deflector plate and be arrested within said receptacles according to their sizes or specific gravity.

In testimony whereof I have affixed my ³⁰ signature.

ALBERTO NORIEGA.
